UNITED STATES PATENT OFFICE.

WALTER W. SIBSON, OF PHILADELPHIA, AND BERTRAND A. PARKES, OF BARON HILL, PENNSYLVANIA, ASSIGNORS TO THE PHILADELPHIA DRYING MACHINERY COMPANY, OF PHILADELPHIA, PENNSYLVANIA, A CORPORATION OF PENNSYLVANIA.

ENDLESS CONVEYER MADE OF PERFORATED METAL.

1,071,269.

Specification of Letters Patent. Patented Aug. 26, 1913.

Application filed September 14, 1911. Serial No. 649,329.

To all whom it may concern:

Be it known that we, WALTER W. SIBSON, of Philadelphia, in the county of Philadelphia and State of Pennsylvania, and BERTRAND A. PARKES, of Baron Hill, in the county of Montgomery and State of Pennsylvania, have invented certain new and useful Improvements in Endless Conveyers Made of Perforated Metal, whereof the following is a specification, reference being had to the accompanying drawings.

Our invention relates to an endless traveling apron or conveyer, having a perforated carrying surface, as for instance, of woven wire mesh, as shown. Instead of making such an apron continuous, which involves well known difficulties, we mount a sectional apron on side chains and make each section co-extensive with one link of the chains. Such aprons are frequently made of large size, and pass around large drums, at the extremities of their travel, in which case it is feasible to use links 10 or 12 inches long, or even more. According to our invention, the paired links are united by cross pieces making rectangular frames by each of which is supported a separate section of the conveyer, thus securing complete freedom of motion as between successive sections.

In the accompanying drawings, Figure I, is a plan view showing a part of one side of an endless conveyer, embodying our invention, sufficient being shown to explain the construction of the whole. Fig. II, is a side elevation of the same. Fig. III, is a central section of the same, on the line III, III, of Fig. I. Fig. IV, is a detail view.

As in Fig. I, only one-half or less of the conveyer is shown, it will be understood that what is there shown must be re-duplicated in order to complete the full width of the conveyer. The carrying chains, of which there are two, one on either side, consist of successive links 1, 1, which are hinged together by pivots 2, as shown. Each link is provided near its ends with bosses or projections 3, slotted to receive cross-pieces 4, which pass from one link on one side to its fellow on the other side, and which are similarly seated at both ends. Each cross-piece 4, is preferably in the form of an angle iron, and in order that the slot in the boss may receive it, it is made of similar angular

shape. If desired, the cross-piece may be permanently attached to the links of the chain making a solid frame, but I prefer for purposes of assemblage and replacement of parts, to construct the pieces which have been described, separately, in which case, each cross-piece after being received within the slot, of the projection 3, is held therein by a cotter pin 6. Two links thus united by two cross-pieces form a rectangular frame, and there is thus provided a separate frame, the sides of which are formed by each pair of links. As shown each cross-piece is centrally hinged to the cross-piece of the next succeeding section, by a hinge 7, but other flexible connections may be employed. Except where the linked sections are short, we further support the metal surface of the conveyer by side lugs 10, projecting from each link and serving also for purposes of attachment.

Corresponding to each rectangular frame thus constituted, is a section of wire netting 11, in length corresponding to the distance between the pivots at the ends of the links. This section of wire netting 11, is conveniently fastened at either end to the cross-piece 4, as for instance, by turning it over the end and under the edge of the cross piece as seen in Fig. IV, but it may be otherwise attached. There is no movement between the section of wire netting and any of the pieces to which it is attached. It will therefore be understood that the entire conveyer consists of a series of links connected at or near their ends by cross-pieces so that each pair of links with its cross-pieces, constitutes a supporting framework, on which is mounted a corresponding section of wire mesh or other material of which the body of the conveyer is composed. The mesh is positively attached to the lugs 10, by means of the rivet or bolt 15, and may be similarly attached to the cross-piece if desired.

It will be noticed that the sheet of wire mesh is so mounted in relation to the links as to bring the end of the sheet where it abuts against the end of the next succeeding sheet as near as possible in line with the axes of the pivots by which the links are hinged together. This is clearly illustrated in Fig. III. As a result of this, as the conveyer passes around the drums and other

supporting mechanism, at the extremities of its travel, there is little or no break in the continuity of the sections of wire netting as the result of the movement between these 5 sections, as they pass around the drum.

Having thus described our invention, we claim:

1. A sectional conveyer of perforated material comprising endless chains with paired links; pivoted connections for successive links; cross-pieces uniting corresponding links, one near each end of each pair of links; and sections of perforated metal surface mounted one upon each rectangular frame, formed by each pair of links, with its two connecting cross-pieces, said sections being attached to the two cross pieces of the frame.
2. In a sectional apron, the combination 20 of paired links hinged to paired links at their extremities; projections near each end of each link with carrying slots; cross-pieces running from link to its fellow separately mounted in the carrying slots; and a section 25 of apron surface corresponding in length to the links and carried between the cross pieces.

3. A sectional apron consisting of carrying chains having paired links; cross pieces uniting each link with its fellow near the 30 ends in the form of a rectangular frame; a section of apron surface mounted within said frame; and supporting lugs projecting in from the sides of the links upon which the surface is additionally supported. 35

4. A sectional wire mesh apron, comprising supporting chains having hinged links; cross-pieces removably mounted between each link and its fellow, near each extremity thereof, whereby each pair of links and the 40 two uniting cross-pieces form a rectangular supporting frame; a section of wire mesh supported in said frame and attached to the cross pieces; and a flexible connection between each cross piece and that of the next 45 adjoining frame.

In testimony whereof we have hereunto signed our names at Philadelphia, Pennsylvania, this eleventh day of September, 1911.

WALTER W. SIBSON.

BERTRAND A. PARKES.
